[57] CLAIM

The ornamental design for pavement marker, as shown and described.

DESCRIPTION

FIG. 1 is a perspective view of a pavement marker showing a new design with the broken lines shown for illustrative purposes only and forming no part of the claimed design;

FIG. 2 is a top elevational view thereof;

FIG. 3 is a bottom elevational view thereof;

FIG. 4 is a left side elevational view, with the opposite side being a mirror image;

FIG. 5 is a front elevational view thereof; and,

FIG. 6 is a back elevational view thereof.
